DOG HEIGHT MEASURE

Alex A. Wambach, Jr., Granville Township,
Milwaukee County, Wis.

Application July 11, 1955, Serial No. 36,916

Term of patent 14 years

(Cl. D52—1)

Fig. 1 is a view in front elevation of a dog height measure embodying my new design; and

Fig. 2 is a top plan view of the dog height measure illustrated in Fig. 1.

I claim:

The ornamental design for a dog height measure, as shown.
